PC(57) **CLAIM**

The ornamental design for a composite sensor, as shown and described.

DESCRIPTION

FIG. 1 is a first perspective view of the front, top, and right sides of a composite sensor showing our new design; FIG. 2 is a second perspective view of the rear, bottom, and left sides thereof;

FIG. 3 is a front view thereof;

FIG. 4 is a rear view thereof;

FIG. 5 is a top plan view thereof;

FIG. 6 is a bottom view thereof;

FIG. 7 is a right side view thereof;

FIG. 8 is a left side view thereof;

FIG. 9 is an enlarged view of a part 9-9 in FIG. 3; and, FIG. 10 is an enlarged cross-sectional view taken along line 10-10 of FIG. 9 at area of 10-10 in FIG. 7.

The broken lines shown represent portions of the composite sensor and form no part of the claimed design. The dot-dash broken lines disclose boundaries of enlarged views and form no part of the claimed design.
